CLAIM

The ornamental design for an electrolyzer, as shown and described.

DESCRIPTION

FIG. 1 is a front view of an electrolyzer;

FIG. 2 is a rear view thereof;

FIG. 3 is a left side view thereof;

FIG. 4 is a right side view thereof;

FIG. 5 is a top plan view thereof;

FIG. 6 is a bottom plan view thereof;

FIG. 7 is first perspective view thereof;

FIG. 8 is second perspective view thereof; and,

FIG. 9 is third perspective view thereof.

The broken lines are for the purposes of illustrating portions of the electrolyzer and form no part of the claimed design.
